UNITED STATES PATENT OFFICE.

CHARLES J. KIRK, OF NEW CASTLE, PENNSYLVANIA.

SHERARDIZING APPARATUS.

1,327,102.

Specification of Letters Patent.

Patented Jan. 6, 1920.

Application filed March 1, 1919. Serial No. 280,130.

To all whom it may concern:

Be it known that I, CHARLES J. KIRK, a citizen of the United States, a resident of New Castle, in the county of Lawrence and

5 State of Pennsylvania, have invented a new and useful Improvement in Sherardizing Apparatus, and do hereby declare the following to be a full, clear, and exact description thereof.

10 My invention relates to sherardizing apparatus.

As is well known the process of sherardizing consists essentially in applying to metallic surfaces pulverulent zinc partially oxidized and subjecting the same to heat in a closed chamber. The present invention relates to the retort or closed chamber within which the process takes place and has special reference to increasing the heating efficiency whereby the time required for effecting the sherardizing may be greatly reduced.

15 To these ends my invention comprises the novel features hereinafter set forth and claimed.

20 In the accompanying drawing Figure 1 is a longitudinal section of a rotary sherardizing retort with my invention applied thereto, and Fig. 2 is a cross-section on the line 2—2 Fig. 1.

25 In the drawing the numeral 2 designates the inclosure for the retort made of fire-brick or other refractory material, and of the usual construction with the hinged-top 3. Within said inclosure is the retort 4 pro-

30 vided with the hollow trunnions 5 which rest upon the idle-rollers 6 mounted in the brackets 7.

The retort 4 is made up of the end plates 8 with the trunnions 5 extending out there-

from, and the electric heating units 9 forming with the lid 10 a hexagonal shaped retort. The heating units 9 may be of any suitable construction.

35 A central heater 11 is provided consisting of the hollow-core 12 with the resistance coil 13 extending therethrough.

The pulverulent zinc and the articles to be sherardized are to be introduced into the retort 4, the lid 10 having been removed. Power is then applied through the sprocket 50 wheel 14 to rotate the retort. By having the separate heater 11 extending centrally of the retort the heat permeates the mass contained within the retort from the center outwardly while the heating units 9 work 55 from the outside in. In this manner the time for the carrying out of the process is greatly reduced due to the greater heating efficiency and the fact that the heat will radiate from the center without loss due to 60 external radiation as in the case of the heating units 9.

What I claim is:

1. In sherardizing apparatus, the combination of a rotary retort, external electric 65 heating units, and an internally arranged electric heating unit.

2. In sherardizing apparatus, the combination of a rotary retort, external electric heating units and internal electrical heating 70 units arranged axially of said retort.

In testimony whereof I, the said CHARLES J. KIRK, have hereunto set my hand.

CHARLES J. KIRK.
